JOHN E. BRASTOW AND EBER K. INGOLDSBY, OF VAN BUREN CENTRE,
NEW YORK.

Letters Patent No. 62,928, dated March 19, 1867.

IMPROVEMENT IN RAILROAD PICKS.

The Schedule referred to in these Letters Patent and making part of the same.

TO ALL WHOM IT MAY CONCERN:

Be it known that we, JOHN E. BRASTOW and EBER K. INGOLDSBY, of Van Buren Centre, in the county of Onondaga, and State of New York, have invented a certain new and useful Improvement in Railroad Picks or Mattocks; and we do hereby declare that the following is a full and exact description thereof, reference being had to the accompanying drawings, making part of this specification.

Figure 1 is a perspective view of our improved pick, with a portion of the handle broken away.

Figure 2 is a longitudinal section of the same.

Figure 3, a perspective view of the iron strap which forms both a fastening for the pick, and a guard or shield for the handle, the said strap being shown as not yet bent to receive the pick-head.

Figure 4, a perspective view of the head end of the handle, showing the mortise for the pick-head.

Like letters of reference indicate corresponding parts in all of the figures.

Our improvement is particularly intended for use on railroads, where the pick is employed in striking under the rails. By constant use for this purpose the handle becomes abraded and worn, and the pick loosened by repeated concussions, so as soon to render it useless.

Our invention consists in forming a straight metallic bar or strap, which is punched with two holes of suitable size, and in such a position that when the straps are afterward bent to form a guard for the exposed sides of the handle, and riveted thereto, the two holes are opposite, and, with the intermediate unbent portion, form an eye or socket to receive the pick-head, into which it may be keyed with an ordinary wedge; thus making the single strap serve the double purpose of a fastening for the pick and guard for the handle.

As represented in the drawings, A is the handle, which is of the usual form, except that instead of being fitted to enter an eye in the pick, it is made with a mortise, a, to receive the solid head of the pick between the sides b b. Over the mortise end of this handle is bent the strap C, which is formed of a straight bar of iron, as shown in fig. 3, having eyes, g g, formed therein, at such positions as that when bent over the handle they will coincide with mortise a in the end thereof. The strap, when thus bent to fit the handle, forms a top band, f, extending over the pick-head, and two guards d d, which extend on opposite sides of the handle a sufficient distance to receive two rivets, c c, which extend through the handle and are headed on each guard-plate d. We are aware that it is common to bend straps around picks or other tools, and rivet or otherwise fasten to the sides of the handle, but in such cases the position of the strap before bending is transverse to the direction of the pick or blade; while in our method the strap is made and fitted longitudinally of the blade of the pick before bending. This secures entirely different results, viz: guarding the exposed sides (those adjacent to the points of the pick;) giving greater strength to resist blows and prying motions thereof; allowing the handle to be made as thick as may be required for strength; and presenting the fibres of the strap longitudinally of the strains to which it is subjected; thus securing the greatest strength of the metal. The importance of this will be apparent when it is observed that nearly all the strains to which picks or mattocks are subjected, are longitudinal of the handle and blades, and rarely, if ever, transverse thereto. The pick-head B is passed through the eyes g g, and is secured by a notch or depression, i, fig. 2, which receives part f of the strap C, and a key or wedge, D, is then driven through the eyes g g, and mortise a, in contact with the inside of the pick, by which combination of devices the pick and handle are firmly secured together. Thus arranged, it will be perceived that while we secure a firm fastening for the pick-head, we also accomplish a great advantage in picks for railroad use especially, by shielding those two sides of the handle which strike against the top or edges of the rails. Unless thus protected, the handles soon become so worn as to be worthless, and have to be replaced. The strap-shield, as above described, is much more effective than an extended socket enclosing the handle could possibly be. The former is light, elastic, and yielding, while the latter would be heavy, cumbersome, and rigid; besides, in the one case, the handle is made of the full size to insure strength, while in the other it would have to be cut down, or else the socket be made very large. In use, also, the strap being light and yielding, causes no jar to the hands of the operator; while in the other case, the rebound is considerable, and the concussion, when the head or handle strikes a rail or other unyielding substance, occasions a painful shock to the arms of the operator. The lightness and pliability of the strap allow it to yield when struck against a rail or other hard substance, so as to

break the concussion, and it may become indented without injuring the fibres of the wooden handle. The strap is so light that it may indent without drawing or loosening the heads of the rivets, so that the pick remains tight in the handle much longer than when composed of heavy parts rigidly connected, for the reason that the vibration of repeated blows will, in time, affect the strongest connections.

We are aware that there are picks in use in which the head is held in a stirrup by wedges, as in the patent of J. E. Emerson, No. 23,358, but in this case the stirrup embraces the handle on its transverse sides, and does not at all protect the handle from injury when striking upon a railroad rail, a purpose for which ours is particularly designed; nor strengthen it to resist strains in the direction of the pick-points and handle; nor does it hold the pick in two solid metallic eyes like *g g*, of the strap C; while the wood of the handle has to be reduced in size to connect with the several parts to which the stirrup is attached, thereby weakening it; and it also requires an iron head to the handle to receive a gib and wedge in addition to the stirrup, thus making the fastening to consist of numerous parts. There are also picks in which the handle is partially protected by ferrules or by plates or guards provided for that purpose alone, but we are not aware of any instance in which the handle is strengthened and shielded, and the pick secured to it by a simple strap applied longitudinally with the head and handle. By this simple mode of construction we secure the following results and advantages:

A secure fastening of the handle and pick without an eye in the latter; increased strength with less weight; reduced cost of manufacture, as the eyes are punched from a straight flat bar, the only forging required being that to bend it to fit the sides of the handle; riveting through the handle in a direction which strengthens it, and prevents its splitting by use; the handle may be made as thick transversely as strength may require, whereas when the transverse strap or socket or eye is used, it has to be reduced at the expense of its strength; it enables the wedge to be used longitudinally of the blade, thereby securing the greatest strength, and gives it a metallic bearing without providing a metal head on the handle.

We claim attaching the pick to its handle by forming a head of the strap C, constructed and applied substantially as and for the purposes herein set forth.

In witness whereof we have hereunto signed our names in the presence of two subscribing witnesses.

JOHN E. BRASTOW,
EBER K. INGOLDSBY.
